UNITED STATES PATENT OFFICE.

FREDRICK J. MCFARLAND, OF BREMERTON, WASHINGTON.

SHEET-METAL-CUTTING TOOL.

Application filed January 9, 1926. Serial No. 80,289.

This invention relates to tools for cutting sheet metal and one of the objects of this invention is to provide a tool for this purpose which may be driven through the sheet metal either by hand or by a steam, pneumatic or electric hammer.

A further object of the invention is to provide a tool of this character which will make perfect cuts of all kinds either straight or curved, right or left, inside or outside, circles of any size larger than one inch in diameter, and will cut right angles or any other cut desired by the operator and which will leave the edges of the metal free from burr, the tool being further capable of cutting an extremely small shaving from the edge of the sheet just as well as it will split the largest sheet.

Still another object is attained by this tool is that the sheets do not have to be turned or handled while being cut and the tool will cut sheet metal in places inaccessible to other tools without removing the metal from its permanent location.

My invention is illustrated in the accompanying drawings wherein:—

Figure 1 is a top plan view of a tool constructed in accordance with my invention;

Figure 2 is a section on the line 2—2 of Figure 1;

Figure 3 is a section on the line 3—3 of Figure 1;

Figure 4 is a section on the line 4—4 of Figure 1;

Figure 5 is a side elevation of the tool constructed in accordance with my invention;

Figure 6 is a section on the line 6—6 of Figure 5;

Figure 7 is a section on the line 7—7 of Figure 5;

Figure 8 is a section on the line 8—8 of Figure 5;

Figure 9 is a front elevation of the cutting tool.

Referring to these drawings it will be seen that the tool comprises a shank 10, which shank is preferably hexagonal in cross section. The cross sectional area of the shank 10 and the length of the shank will depend, of course, upon the work to be accomplished. The shank is formed at one end with a cutting head formed to provide two wings 11 and 12, which on the line 8—8 of Figure 5

are laterally offset with regard to each other so that the inner flat face 13 of the upper wing coincides with the inner flat face 14 of the lower wing. The lower wing 12 is extended in advance of the upper wing 11 and is somewhat pointed at its extremity while the upper wing 11 is rounded at its extremity. It will be seen from Figure 5 that the inner edge faces 15 and 16 of the head constitute two sides of a reentrant angle, the apex of this angle being disposed approximately on the line 7—7 of Figure 5. One side face of each blade or wing 11 and 12 is flat, as before remarked, and the top and bottom faces are deformations or modifications of the faces of the hexagonal shank 10.

This tool is to be formed of steel and the point of the wing 12 is to be driven into the metal so that the sheet of metal will be disposed at right angles to the faces 13 and 14 and against the apex of the reentrant angle formed by the faces 15 and 16, this angle being (for a tool capable of use for sheet metal having a thickness of .0625 mill. or less) approximately 22°.

For making cuts that have their beginning at the edge or margin of the sheet the reentrant angle or cutting edge of the tool is disposed against the edge of the sheet at the desired point, keeping the shank of the tool almost parallel with the surface of the sheet. The tool is then driven through the sheet by means of a hammer following the desired line. This will force the sheet on one side, under one blade or wing of the tool and on the other side above the other blade or wing. If the shank is held exactly parallel to the surface of the sheet being cut, both cutting edges of the sheet will be slightly curved but if the shank of the tool is held at an angle equal to the angle of one side of the V-shaped notch 16, the lower sheet will be left perfectly smooth and straight while the other side of the cut will be curved thus giving clearance for the operator's hammer and hand.

For cuts that are wholly within the sheet and do not reach the margin or edge of the sheet the longer and pointed end 15 of the blade 12 is placed against the sheet near the starting point of the cut desired and the shank of the tool is kept at about 90° from the surfaces of the sheet. The tool is then

driven inward until the point of the blade punctures the sheet and then continue driving and bring the shank of the tool down until it is almost parallel with the surface of the sheet, following the line of desired cut.

In making short curves the tool will adjust itself to the proper lateral angle to make the desired curve, requiring only guiding and driving by the operator to make the cut desired.

As above stated, the long pointed blade or wing 12 as shown in Figure 5 is used for puncturing the sheet where the cut is wholly within the sheet. This requires the upper blade 13 to be rounded on its edge in order to slide on top of the sheet and not dig in thus letting the sheet reach the apex of the V-shaped notch or cutting edge of the tool freely. Both blades recede from the center line of the shank from the apex of the V-shaped notch to the point where the blades merge into the shank, thus giving the clearance required in cutting small circles and sharp curves.

This device will make smooth cuts of all kinds either in a curved or straight line at the option of the workman, and can be driven forward with a common hammer or by a pneumatic or electric hammer and will make right angular cuts with the same facility that it does curved or straight cuts. In actual practice it has been found that this tool will do the work of expensive power machines in less than one half the time and accomplish much better results. The edges of the metal will be free from any burr and even small shavings may be cut from the edge of the sheet with ease. The sheets do not have to be turned or handled while being cut but may be simply laid on a bench or floor and cut by a single operator without help or assistance. The tool does not require sharpening, at least for a very long time.

In actual practice it has been found that used with a small sized pneumatic hammer the tool will cut 17^{1/2} of 22 gauge galvanized iron per minute, 14^{1/2} of 20 gauge galvanized iron per minute, 9^{1/2} of 18 gauge, 6^{1/2} of 16 gauge and 2^{1/2} of 14 gauge in a minute, while with the larger size pneumatic hammer it will cut $\frac{3}{16}$ thick plate easily. This tool has been used to cut a hole having a circumference of 100" in the center of a sheet of 18 gauge galvanized steel and has cut this hole in one and one half minutes with only one person employed, while with a hammer and cold chisel and file to smooth the cut the best time made was thirty minutes by one mechanic and one helper. Furthermore, this tool will cut sheet metal in places inaccessible to other tools without any necessity of removing the sheet being cut. Thus, it may be used for cutting holes in pipes, boiler

cases, etc., without removing them from their permanent locations. Obviously the tool will be made in larger or smaller sizes and the blades or wings will also vary in their dimensions and in the angle which the two faces 15 and 16 bear to each other.

I do not wish to be limited to the exact formation of the tool as illustrated, as this may be varied in many ways without departing from the spirit of the invention as defined in the appended claims.

I claim:

1. A sheet metal cutting tool having a shank and a cutting head, the cutting head being formed with an upper and a lower 80 blade or wing, the wings at their forward ends being separated from each other by an approximately V-shaped space, said wings being laterally offset with relation to each other, the inner face of each blade being flat 85 and disposed in approximately the same plane.

2. A sheet metal cutting tool having a shank and a cutting head, the cutting head being formed with upper and lower wings or 90 blades, the wings being laterally offset with relation to each other, and the inner edges of the wings being extended convergently in- 95 ward into intersecting relation.

3. A sheet metal cutting tool having a 95 shank and a cutting head formed thereon, the cutting head being formed to provide upper and lower laterally opposed blades, the inner faces of each blade being flat and the inner faces of both blades being disposed 100 in the same plane, the blades at their forward ends being separated by a reentrantly angled opening, and the lower blade or wing extending beyond the upper blade or wing.

4. A sheet metal cutting tool having a 105 shank and a cutting head, the cutting head being widened and flattened and twisted with relation to the shank to provide two wings or blades disposed in offset relation to each other and formed to provide flat 110 inner faces disposed in the same plane, the upper wing at its forward end being rounded and the lower wing being pointed and projected beyond the upper wing, said upper and lower blades or wings having their inner 115 edge faces reentrantly angled.

5. A sheet metal cutting tool having a cutting head, formed with a reentrantly angled cutting edge, the portions of the head above and below the cutting edge having 120 their faces disposed in parallel planes but integral and laterally offset with relation to each other.

6. A sheet metal cutting tool having a shank and a cutting head, the cutting head 125 being flattened to provide two wings or blades disposed in laterally offset relation to each other and formed to provide flat inner faces disposed in the same plane, the upper wing at its forward end being pointed and 130

extended beyond the upper wing, said upper and lower wings or blades having their inner edge faces reentrantly angled and transversely inclined, the transversely inclined faces of one blade intersecting the flat inner face of the other blade, and said inclined faces receding from the center of the line of the

shank from the apex of the V-shaped notch to the point where the blades merge into the shank.

10

In testimony whereof I hereunto affix my signature.

FREDRICK J. McFARLAND.
